ABSTRACT: A Zener diode voltage reference circuit whose output is maintained at exactly the Zener voltage irrespective of changes in the input voltage. More particularly, since the voltage appearing across a Zener diode fluctuates slightly with changes in the Zener current, exact regulation is accomplished by maintaining the current flowing through the diode at a constant value; furthermore, the Zener current is held constant by adding to the circuit a second Zener diode which serves to extract from the first Zener diode all the current which would cause a voltage fluctuation.

ZENER DIODE REFERENCE CIRCUIT INDEPENDENT OF INPUT VOLTAGE CHANGES

BACKGROUND OF THE INVENTION

1. Field of the Invention

The present invention relates generally to voltage reference circuits and more particularly to a new and improved Zener diode voltage reference circuit that maintains an exactly constant voltage output regardless of input voltage changes.

2. Description of the Prior Art

In the past, various voltage regulators have been utilized to provide an approximate voltage reference source. However, a voltage level output that would remain at exactly one voltage level, regardless of variations in the input source or other influences in the surrounding environment, has not been attainable. Various electronic means and methods have heretofore been employed in the previously developed current and voltage regulators in an attempt to obtain an exactly constant output. Such means included diodes, transistors, feedback loops, and Zener diodes. However, the instant invention, in utilizing two Zener diodes, produces an exact and nonvariant output voltage.

SUMMARY OF THE INVENTION

The instant invention can be used in any low current application wherein a constant voltage reference is desired. A great number of possible uses can be imagined, and mentioning only a small number of them, the instant invention would improve the operation of analog-to-digital converters, digital-to-analog converters, thermal reference regulators and voltage comparators. It is therefore obvious that the subject invention could be used in a plurality of applications.

It is therefore the primary object of the present invention to provide a new and improved voltage reference circuit.

A further object of the invention is to provide a voltage reference circuit that will yield a constant voltage output regardless of changes in the input voltage.

Another object of the invention is to provide a voltage reference circuit utilizing two Zener diodes.

A still further object of this invention is to provide a voltage reference circuit whereby one Zener diode serves to extract fluctuations of the input current such that the other Zener diode will receive only exact current input.

An additional important object of the invention is to provide a voltage reference circuit wherein the variation of output voltage with input voltage can be varied in direction and magnitude by merely adjusting the impedance of one of the circuit resistors. In particular, it is possible to obtain zero variation of output voltage with input voltage.

Still another object of this invention is to provide a voltage reference unit utilizing two Zener diodes such that the combination of the individual temperature effects of each diode is to yield a total flat temperature characteristic.

Other objects, functions and characteristic features of the instant invention will become more apparent as the discussion of the subject invention proceeds and will become obvious in part from the detailed description of the preferred embodiments and in part from the drawings.

BRIEF DESCRIPTION OF THE DRAWINGS

FIG. 1 is a schematic showing a prior art voltage regulator;

FIG. 2 is a plot of current to the Zener diode versus input voltage for the circuit of FIG. 1;

FIG. 3 is a schematic diagram of the instant invention;

FIG. 4 is a graph of the transistor collector current versus the input voltage for the circuit of FIG. 3; and

FIG. 5 is a plot of the main Zener diode current versus the input voltage of the circuit of FIG. 3.

In FIG. 1, there is shown a conventional Zener diode voltage reference circuit consisting of serially connected Zener diode 1 and resistor 2 and in FIG. 2, there is shown a curve of the Zener current versus the input voltage of the circuit shown in FIG. 1. It can be readily observed that as the input voltage

increases, so does the current of the Zener diode 1, assuming, of course, the voltage has exceeded the breakdown voltage level of the Zener diode 1. Therefore, for any variation in input voltage there is an accompanying variation of the Zener diode current which, in turn, affects the stability of output voltage.

Referring now to FIG. 4, there is shown the voltage-current curve of a voltage reference circuit similar to that shown in FIG. 1. It should be noted, however, that the voltage required to turn on the Zener diode 1 shown in FIG. 1, is V_1 , and the voltage required to turn on the Zener diode whose characteristics are shown in FIG. 4 is $V_2 + V_{BE}$ (V_2 being greater than V_1).

It should now be evident that if a voltage reference circuit whose characteristics are shown in FIG. 2 is connected to a voltage reference circuit whose characteristics are shown in FIG. 4 (the FIG. 4 reference being inverted), the main Zener diode in the resultant circuit has the characteristics shown in FIG. 5. In said resultant circuit no current would flow through the main diode until the input voltage reaches V_1 (that voltage necessary to run on the main diode); whereupon the current through this diode increases, unaffected by the second diode, until the input voltage reaches $V_2 + V_{BE}$ (that voltage required to turn on the second diode). Once both diodes are conducting the current flowing through the main diode would remain at a constant value, since the second diode is connected in the circuit in such a manner that all unwanted current is extracted from the main diode. And, as noted above, since the current flowing through the main diode is held at a constant value, the voltage across this diode is constant.

In reference now to FIG. 3, there is shown the voltage reference circuit of the present invention, said reference circuit having the characteristics as shown in FIG. 5. In FIG. 3 there are serially connected circuit input terminal 3, secondary extractor Zener diode 4, transistor 5, and resistor 6, the input of said resistor 6 being connected to the emitter of said transistor and the output of said resistor 6 being connected to ground 7. The purpose of the transistor 5 is to invert the effects of Zener diode 4. Also included in the improved voltage reference circuit is serially connected variable resistor 8, resistor 9, main Zener diode 10, and ground connection 11. Resistor 9 is included in the preferred embodiment to prevent excessive input current from being drawn into input terminal 3 when the voltage at said input terminal exceeds the operating range of transistor 5. An output terminal 12 is electrically connected between resistor 9 and main Zener diode 10. Also, the collector of the transistor 5 is connected in electrical parallelism between resistor 8 and resistor 9, as shown at 13. Finally, the resistor 8 is connected to the input terminal 3.

As noted above, the main Zener diode 10 does not conduct until the voltage reaches the breakdown voltage level of said diode. When said breakdown voltage level is reached, the Zener current increases proportionately, with a slope equal to

$$\frac{1}{R_8 + R_9}$$

and continues therein until voltage

$$V_2 + V_{BE}$$

is obtained, whereupon the Zener current increases with a slope of

$$\frac{1}{R_8 + R_9} \left(1 - \alpha \frac{R_8}{R_9} \right) \approx 0$$

where V_2 is the voltage across the secondary extractor Zener diode 4 and V_{BE} is the voltage across the base emitter junction of transistor 5. The variable α is the common-base current gain of transistor 5. Thus, in this manner, once the input voltage reaches a level wherein both diodes are turned on, the output voltage remains unchanged irrespective of fluctuations in the input; all current in excess of the current desired to pass through the main diode 10 is drawn to ground 7 through the collector-emitter path of the connecting transistor 5.

If the output voltage is desired to exhibit small changes for accompanying changes in voltage input, this can be accomplished by varying the resistance of resistor 8. In this manner, the slope of the curve in FIG. 5 that is normally equal to zero can be changed to reflect small changes in voltage regulation. 5

Another added effect that the combination of the two Zener diodes exhibits is a flat temperature characteristic, such that the temperature variation in one Zener diode is compensated for by the other diode and the base-emitter voltage of transistor 5 whereby for nominal changes in operating temperatures, there are little, if any, accompanying changes in the output voltage. 10

For determining the value of current through the main Zener diode 10, a nodal equation at 13 would be;

$$\frac{V_{in} - V_x}{R_8} - \frac{V_x - V_1}{R_9} \approx \left(\frac{V_{in} - V_2 - V_{BE}}{R_6} \right) \alpha$$

Where the V_{in} is the voltage at input terminal 3,

V_x is the voltage at 13

V_1 is the voltage across Zener diode 10

V_2 is the voltage across Zener diode 4

R_8 is the impedance of resistor 8

R_6 is the impedance of resistor 6

R_9 is the impedance of resistor 9

Assuming α equals 1, and rearranging, the following equation 25 is obtained:

$$I_z = \frac{V_{in} - V_1 - \frac{R_8}{R_6} (V_{in} - V_2 - V_{BE})}{R_8 + R_9}$$

where I_z is the main Zener diode current.

However, for

$$\frac{\partial I_z}{\partial V_{in}} = 0 = \frac{\left(1 - \frac{R_8}{R_6}\right)}{R_8 + R_9}$$

and by making

$$R_8 \approx R_6 \approx R,$$

the main zener diode current becomes

$$I_z = \frac{V_2 + V_{BE} - V_1}{R_9 + R}$$

In conclusion it will be clear that the main Zener diode current will be independent of the input voltage and accompanying fluctuations. 45

In a practical embodiment, where α is slightly less than unity, and the Zener diodes have small internal resistances, R_8 is set slightly larger than R_6 to obtain the desired result, namely

$$\frac{\partial I_z}{\partial V_{in}} = 0$$

I claim:

1. A voltage regulator circuit for producing constant output voltage from a variable input voltage comprising:

first circuit means connected between said variable input voltage and ground, said first circuit means including:

a resistance means connected to said variable input voltage and

a first Zener diode serially connected between said re-

sistance means and ground.
an output terminal connected to the junction of said resistance means and said first Zener diode, and
second circuit means connected in parallel with said first circuit means and being responsive to variations in said variable input voltage for diverting said voltage variations away from said first circuit means to ground to insure that said first circuit means receives a constant current effective to insure that the voltage appearing at said output terminal remains constant regardless of variations in said input voltage.

2. The regulator circuit as defined in claim 1 wherein said resistance means consists of:

a variable resistor connected to said input current supply, and
a first, fixed resistor serially connected between said variable resistor and said first Zener diode, whereby adjustment of said variable resistor causes said regulator circuit to provide a variable amount of voltage regulation in both magnitude and direction. 20

3. The regulator circuit as recited in claim 2 wherein said circuit means comprises:

a second Zener diode having an anode and cathode and having a greater voltage breakdown level than that of said first Zener diode,
a transistor having a base, collector and emitter,
a second fixed resistor,
the cathode of said second Zener diode being connected to said input supply and the anode of said second Zener diode being connected to the base of said transistor, and
the collector of said transistor being connected at the junction of said variable resistor and first fixed resistor, and
the emitter of said transistor being connected by said second fixed resistor to ground. 30

35. 4. The circuit as recited in claim 1 wherein said resistance means consists of first and second serially connected resistors, and wherein:

said second circuit means comprises;
a second Zener diode having an anode and cathode and having a greater voltage breakdown level than that of said first Zener diode,
a transistor having a base, collector and emitter, and
a third fixed resistor,
the cathode of said second Zener diode being connected to said input supply and the anode of said second Zener diode being connected to the base of said transistor, 45

the collector of said transistor being connected at the junction of said pair of serially connected resistors and the emitter of said transistor being connected by said third fixed resistor to ground. 50

5. The circuit as defined in claim 4 wherein the values of that resistor of said serially connected pair which is connected to the input supply is approximately equal to the value of said third fixed resistor such that a constant level of output voltage will be obtained. 55

6. The circuit as described in claim 4 wherein the value of that resistor of said serially connected pair which is connected to said input supply is variable over a range which includes the value of said third fixed resistor. 60
